[57] ABSTRACT

An automatic packing apparatus usable at the checkout counter of a super market comprises a sack producing section, a goods introducing section, a sack top sealing section and a delivery section. A sack produced in the sack producing section is conveyed to the goods introducing section in which goods are introduced into the sack which is then conveyed to the sack top sealing section in which the loaded sack is sealed at the top to form a package of goods which in turn is conveyed to the delivery section. The apparatus eliminates the need for a sacker and simplifies the registering operation to thereby save labor.

FIG. 29

AUTOMATIC PACKING APPARATUS

BACKGROUND OF THE INVENTION

1. Field of the Invention

The present invention relates to an automatic packing apparatus which is capable of producing sacks from a packing material and packing various kinds of goods into respective sacks to form packages of goods. The apparatus is particularly, but not restrictively, suited for use at the check-out counter of a supermarket where a sacker is needed in addition to a cashier.

2. Description of Prior Art

In many supermarkets a customer picks up required goods into a basket and carries it to a check-out counter where the basket is placed on a table. A cashier will check the prices for the goods and insert the prices into a registering machine while displacing the goods from the basket into another empty one. A sacker will then pick out the goods from the other basket and pack the goods into a sack. In the course of the operation, if the goods include wet goods such as food, the sacker is required to preliminarily pack the wet goods into a small sack. In a case where there is no sacker, the cashier is required to carry out all of the operations with the result that the customer is kept waiting for her goods for a long time.

Some supermarkets employ a procedure in which the goods checked by a cashier are placed on a conveyor so that the goods are conveyed to a sacking position in which the customers are required to pack their goods into sacks by themselves. The packing position is required to have sufficient area to enable several customers to perform their packing operations at the same time. In addition, the procedure is disadvantageous in that sacks are laid out of control at the market.

In order to eliminate the problems discussed above, there has been devised an automatic sacker in which sacks are produced and loaded sacks are sealed, both in a goods introducing section of the sacker. With the arrangement of this sacker, there are required a time for the sealing of a loaded sack at the top thereof and for the delivery of the sealed sack and a time for the preparation of another sack under a goods inlet opening in the machine. The procedure must be completed during the time from the moment when a packing initiation button is depressed for the packing of goods of a preceding customer to the moment when goods of the next customer are introduced into the machine. The total amounts of the time required for the procedure are longer than the time required by a manual packing operation.

SUMMARY OF THE INVENTION

The present invention has as an object to provide an improved apparatus for automatically packing goods which can be advantageously used in a supermarket to shorten the time required for registering and packing at the check-out counter for thereby saving labor.

It is another object of the present invention to provide a method of producing sacks usable with the apparatus discussed above.

According to one aspect of the present invention, there is provided packing apparatus comprising means for producing sacks from a liquid impermeable packing material such as plastic film, means for introducing goods into each of said sacks, means for sealing the

loaded sack adjacent the top thereof to pack the goods, means for delivering the packed goods, and conveyor means supporting the sacks at a predetermined pitch and operative in response to a packing initiation signal to convey the sacks to succeeding processing positions.

According to another aspect of the present invention, there is also provided a method of producing sacks from a length of tube of a film material, the tube having a substantially flat ribbon-like configuration with opposite sides of the tube being inwardly folded into the thickness of the ribbon and with the outer edges of each of the folded sides being disposed in close contacting relationship with each other, said method comprising the steps of forming a roll of the ribbon-like tube, feeding the tube from the roll with the outer edges of each of the folded sides being separated, lifting the tube through sealing and cutting means, stopping the tube when it is lifted a predetermined distance, and causing said sealing and cutting means to seal and sever the tube to form a sack having opposite sides partially folded inwardly.

The above and other objects, features and advantages of the present invention will be apparent from the following description with reference to the accompanying drawings.

BRIEF DESCRIPTION OF DRAWINGS

FIG. 1 is a perspective view of an embodiment of the automatic packing apparatus of the present invention;

FIGS. 2A and 2B are perspective views of large and small sacks produced and used by the apparatus of the invention;

FIG. 3 illustrates in diagrammatic longitudinal sectional side view the outline of the apparatus of the invention;

FIG. 4 illustrates in diagrammatic side elevation the arrangement in a sack producing section of the apparatus of the invention;

FIG. 5 is a front elevational view of a part of the sack producing section;

FIG. 6 is an enlarged side elevation of a part of the sack producing section as viewed along line VI — VI in FIG. 3;

FIG. 7 is an enlarged perspective illustration of a chuck unit as viewed in a direction indicated by an arrow VII in FIG. 5;

FIG. 8 is a sectional view taken along line VIII — VIII in FIG. 7;

FIG. 9 is a top plan view of the chuck unit shown in FIG. 7;

FIG. 10 is a cross-section of the chuck unit taken along line X — X in FIG. 9;

FIG. 11 is a partially chuck top plan view of tube pinching portions of the chuck unit;

FIG. 12 is an enlarged perspective view of the tube pinching portions shown in FIG. 11;

FIG. 13 is an enlarged front view of a part of the sack producing section shown in FIG. 5 illustrating the tube and separators;

FIGS. 14 - 1 (A) and (B) are fragmentary sections of a separator taken along lines XIVA — XIVA and XIVB — XIVB in FIG. 13, respectively;

FIGS. 14 - 2 (E), (F), (G) and (H) are sections taken along lines XIVE — XIVE, XIVF XIVG — XIVG and XIVH — XIVH in FIG. 13, respectively;

FIG. 15 is an enlarged perspective view of sealing and cutting means with a part being cut off;

FIG. 16 is a cross-sectional view of the sealing and cutting means shown in FIG. 15;

FIG. 17 is a view taken along line XVII — XVII in FIG. 16;

FIG. 18 is an electric circuit diagram employed in the sealing means;

FIG. 19 is a diagrammatic plan view of a sack conveyor illustrating the shapes of a sack in different stations;

FIG. 20 is a diagrammatic side elevational view of the conveyor shown in FIG. 19;

FIG. 21 is an enlarged perspective view of a guide for a conveyor chain;

FIG. 22 is a perspective view of a mechanism for actuating grippers on the conveyor chains;

FIG. 23 is an enlarged side elevation of a gripper shown in FIG. 22;

FIG. 24 is a perspective view of a sack folding means;

FIGS. 25A and B are diagrammatical fragmentary views of the sack folding means in different positions;

FIG. 26 is a diagrammatical illustration of the time schedule of the operation of the apparatus;

FIG. 27 is a front elevation of a modified sack producing mechanism;

FIG. 28 is an enlarged top plan view of a modified chuck mechanism taken along line XXVIII — XXVIII in FIG. 27; and

FIG. 29 is a view similar to FIG. 24 but illustrating a modified sack folding means.

DESCRIPTION OF PREFERRED EMBODIMENTS

FIG. 1 illustrates an embodiment of the apparatus of the present invention having a layout substantially similar to that of one of the lanes heretofore employed in a supermarket. Namely, purchasers are caused to move in a direction indicated by an arrow Y along the side face of the apparatus remote from the side face thereof adjacent the counter and place on a table 4 baskets Z filled with required goods. A cashier stands in front of the counter as indicated by foot patterns 9 and removes by her left hand the goods one after another from each basket Z while checking the price for each of the goods and introduces the checked goods into the apparatus through either of inlet openings 2 and 3. The prices for the goods are keyed-in into a register 6 by the right hand of the cashier.

The inlet opening 2 is designed to receive small sacks 13a each having a height L₂, as shown in FIG. 2B, while the inlet opening 3 is adapted to receive large sacks 13 each having a height L₁, as shown in FIG. 2A. As will be apparent from FIGS. 2A and 2B, the sacks 13 and 13a are of the type which have opposite side edge portions folded inwardly. The sacks are made from lengths of tubes of a liquid impermeable material such as a plastic film. The tubes are sealed by welding to form bottoms of the sacks 13 and 13a. In the case where the tubes are made from a transparent or translucent film, the tubes are preferably provided with non-transparent bands so that resultant sacks are detected in the apparatus by means of a photo-electric tube. Alternatively, sacks may be detected by means other than a photo-electric tube, such as, for example, a micro switch. In such an alternative case, the non-transparent bands are unnecessary.

When all of the goods from a basket Z are introduced into the apparatus, the cashier will actuate a total key on the register 6 to know the sum of the prices for the

goods. After the cashier receives money, she will push a packing initiation push-button 5.

The apparatus has a pair of lines which include the inlet openings 2 and 3 and which are operable independently from each other. In several seconds from the actuation of the push-button 5, the goods are packed in a sack, i.e., the sack in which the goods are placed is sealed at its top to form a package which is conveyed to one of the delivery positions 11 and 12.

10 Adjacent the rearward or trailing end of the apparatus, the same is provided with a work table 1 on which a purchaser may put her own basket or bag so as to place the package of goods therein. The sack forming tubes are prepared in the form of rolls 8 and 8a disposed under a register table. A set of control means 10 for the apparatus is disposed beneath the delivery position 11 and 12.

The general outline will then be described with reference to FIG. 3. The apparatus is generally divided into four sections, i.e., a sack producing section I, a goods introducing section II, a sack top sealing section III and a delivery section IV. In the sack producing section I, predetermined lengths of tubes are drawn out of the rolls 8 and 8a and welded to form bottoms for large and small sacks 13 and 13a. The tubes are then severed at places immediately after or upstream of the welded portions to separate the sacks from the remaining lengths of tubes. The thus produced sacks are conveyed to goods introducing section II in which the sacks are positioned under the inlet openings 2 and 3 with their tops held open and the bottoms supported by belt conveyors so as to facilitate insertion and removal of goods into and out of the sacks and allow the weight of the goods to be carried by the belt conveyor. The sacks with the goods therein will then be moved to the section III in which the sacks are sealed, by welding, substantially along their top edges to packages of goods which are then conveyed by belt conveyors to the delivery section IV.

It will be appreciated that FIG. 3 illustrates only one of two sack producing and packing lines included in the apparatus of the present invention. The difference between the two lines resides only in the difference in the sizes or heights of the sack produced and sealed in these lines.

50 The sack producing section I will be described in detail with reference to FIGS. 4 through 18. FIG. 4 diagrammatically illustrates the paths of travel of film tubes 13' and 13a' for the large and small sacks 13 and 13a in the sack producing section. The tubes 13' and 13a' are respectively drawn from the rolls of tubes 8 and 8a and moved around sets of intermediate guide rollers 29 and 29a to seal and cutting means which are generally indicated by 28 and 28a, respectively, and which are of a conventional type having heat source portions 24, 24a, spring-loaded pressing portions 25, 25a and well-known knives of a metal 26, 26a, respectively.

55 Sets of projectors and photoelectric tubes 30 and 30a are provided in the paths of the tubes 13' and 13a' adjacent the rolls 8 and 8a' respectively, to detect a lack of supply of the tubes from the rolls for informing an operator of this fact. An empty roll may be replaced by another new roll and the leading end of the tube from the new roll will be connected to the trailing end of the tube from the last, removed roll by an appropriate

means such as an adhesive tape. Tables 31 and 31a are provided for the tape connecting operation.

Because the mechanisms for the production of large and small sacks 13 and 13a are substantially identical except the distances through which the tubes are advanced each time when large and small sacks are produced, only the mechanism for the production of the large sacks 13 will be presently described in detail in connection with FIG. 5. As discussed previously in connection with FIG. 2, the tube 13' used to form sacks 13 has inwardly folded portions 35 to provide four edges. The tube is wound on the roll 8 in such a manner that the tube is collapsed with the two outer edges of each of the inwardly folded portions being in close contact with each other. After the tube 13' is moved past the last guide roller 29, a pair of guides or separators 38 and 38' are provided to separate the two contacting edges of each folded portions 35 so that the four separated edges are pinched, by lifting chucks to be described later. The tube is intermittently lifted a distance L_1 , which is substantially equal to the height of a large sack 13, to a position in which the tube is gripped, as shown in FIG. 6, at the tops of the four separated side edges by grippers 37 provided on chain conveyors 36 for the packing step. Thereafter, the tube is welded and severed to form a large sack 13 which is conveyed to the next section II.

Seal and cutting means 28 are disposed at a level below the distance L_1 from the top edge of the tube which is gripped by the grippers 37. The sealing means 28 are adapted to seal the tube 13' along a sealing line positioned slightly upwardly of a severing line 39 along which the tube is severed. A pair of left and right chuck units 40 and 41 for pinching the four separated side edges of the tube to lift the same are disposed in such a manner that the units have their tops positioned below the severing line 39 a distance b which is slightly larger than the width a of a narrow lateral area prepared along the top edge of the tube 13' so as to enable the grippers 37 to grip the tube. The chuck units 40 and 41 are so designed that they are lifted the distance L_1 , while pinching the tube 13' and are lowered to the initial position with the tube released therefrom and then the operation is cyclically repeated. The sealing and cutting means 28 are designed to act on the tube 13' when the chuck units are in their lowered positions.

The left and right chuck units 40 and 41 are interconnected by a connecting bar 42 which is slidably mounted on an upstanding guide post 43 and is secured at one end to a conveyor mechanism having a path of travel parallel to the guide post 43. More specifically, the left end of the connecting bar 42 is secured to a link member 45 on a chain conveyor 44 which is driven by a motor 46 so as to operate the bar 42. Micro switches 47 and 48 are provided to deenergize the motor 46 when the bar 42 reaches the upper and lower ends of its intended stroke. The bar 42 is provided at its other end with a roller 49 which is guided by a guide channel provided by an upstanding right hand post 50 so that the connecting bar 42 is prevented from otherwise being laterally oscillated during upward and downward movement.

The right hand chuck unit 41 is mounted on the bar 42 for limited movement with respect thereto in the longitudinal direction of the bar. The chuck unit 41 has a roller 51 which is adapted to ride on a cam 52 when the bar 42 is in its lowered position and the chuck units

are caused to pinch the tube 13'. As the bar 42 is moved upwardly, the roller 51 is moved upwardly off the cam 52 to allow the chuck unit 41 to be urged outwardly or rightwardly by an associated compression spring 53 with a result that the tube 13' is stretched widthwise to ensure that the tube is gripped by the grippers 37.

The chuck units 40 and 41 have substantially the same structures. Thus, the structural detail of the chuck unit 41 only will be described hereunder with reference to FIGS. 6 through 10.

The opposite outer edges of respective inwardly folded portions 35 of the tube 13' are separated by the guides or separators 38 as described above. The chuck units 40 and 41 are provided with clamp blocks 54 (only one of which is shown) which extend toward each other. The clamp block 54 is so positioned as to laterally extend between the separated outer edges of one of the inwardly folded portions 35 of the tube 13' toward the axis thereof. A pair of levers 55 are pivotally mounted by a pin 56 on the clamp block 54 in such a manner that the levers are rotatable about the pin 56 toward and away from the side faces of the clamp block 54 to cooperate therewith to pinch and release the outer edges of one of the inwardly folded portions 35 of the tube 13'. A tension spring 57 is provided between the levers 55 to bias them toward each other. Each of the levers 55 has a rearward extension 59 having a rearward end on which a roller 58 is mounted. A cam 60 is adapted to be forced into the gap between the rollers 58 on the opposite rearward extensions 59 of the levers 55 to rotate the same away from the side faces of the clamp block 54 so that the tube 13' is released. The chuck unit 41 is designed such that it is lifted when the tube 13' is pinched by the clamp block 54 and the levers 55 and that the chuck unit is lowered with the tube 13' being released from the clamp block 54 and the levers 55.

The cam 60 is rigidly mounted on a rod 61 which is connected to a solenoid 62 for actuating the cam. A return spring 63 is provided to always bias the cam 60 away from the rollers 58. A bracket 64 supports the chuck unit 41 in its entirety. The unit 41 includes a guide block 65 which is slidable with respect to a guide way 66 secured to the bar 42 for the lateral movement of the chuck unit 41 relative to the bar 42 by means of the roller 51, cam 60 and the spring 53, as described in connection with FIG. 5. The rod 61 of the solenoid 62 has its upper end portion 70 extending upwardly through a top plate 71 which forms a part of the bracket 64. The rod end portion 70 may be manually pushed down to open the levers 55 either when a tube 13' is initially set on the apparatus or in a case where the chuck unit 41 has accidentally failed to grip the edges of the tube.

Referring to FIGS. 11 and 12, a pair of cushioning plates 67 of a resilient material such as polyurethane are advantageously mounted on the opposite side faces of the forward end portion of the clamp block 54 in such a manner that the plates 67 extend inwardly and upwardly beyond the inner and upper faces of the block 54. Similarly, a cushioning plate 68 of a similar resilient material is mounted on the lateral inner surface of each of the levers 55 in such a manner that the plate 68 is moved into face to face contact with the plate 67 when the corresponding lever 55 is rotated toward the block 54 so that each of the cushioning plates

68 cooperates with one of the cushioning plates 67 to pinch one of the outer edges of one of the inwardly folded portions 35 of the tube 13'. When the sealing and cutting means 28 act on the tube 13', the separated edges of the folded portions 35 of the tube 13' are inwardly moved into a close contact relationship to each other as shown by broken line in FIG. 6. The resilient cushioning plates 67 are advantageously deformed or bent inwardly, as shown by broken lines in FIG. 6, to facilitate the inward movement of the edges of the tube 13' and thus the sealing and severing operation by the sealing and cutting means 28. After the tube 13' is severed along the severing line 39, the cushioning plates 67 are restored to their initial or normal straight positions to assure that the outer edges of the inwardly folded portions 35 are again separated from each other so as to be gripped at their severed upper ends by the grippers 37 when the chuck unit 41 is moved upwardly to its elevated position.

Pins 69 having sharp inner ends extend through each lever 55 and the corresponding cushioning plate 68. The sharp inner ends of the pins 69 are adapted to be driven into the associated inner cushioning plate 67 when the levers 55 and the outer cushioning plates 68 are moved toward the clamp block 54 and the inner cushioning plates 67. At that time, the sharp inner ends of the pins 69 pierce through the tube 13' at the portions adjacent the outer edges of the inwardly folded portions 35 to prevent the edges from being withdrawn from the chuck unit 41 when tension is exerted to the tube 13' during the sealing and severing operation by the sealing and cutting means 28.

Referring to FIGS. 13 to 14 - 2, the guide plates or separators 38 and 38' are inclined at an angle α with respect to a line transverse to the axis of the tube 13' in such a manner that the inner end portions of the separators are advanced further than their outer end portions with respect to the movement of the tube as indicated by an arrow shown in FIG. 13. Tests have shown that the angle of advancement α is preferably on the order of from 10° to 28°. Each of the separators 38 and 38' has a substantially parallelogramic configuration, the inner leading corner of which is cut away to provide a leading edge substantially perpendicular to the axis of the tube 13'. The perpendicular leading edge is connected to the inclined leading edge of the separator 38, 38'. The inclined leading edge extends into the space between the folded portions 35 of the tube 13' a distance c which preferably is one half the depth or the width g of the folded portions 35. On the other hand, each separator extends into the folded portions 35 a distance d , as measured between the inner end of the separator and the corresponding outer edges of the tube 13, the distance d being somewhat less than the dimension g so that a gap is defined between the inner edge or folding line of the folded portions 35 and the inner end of each separator. Each of the separators 38 and 38' has such cross-sectional and longitudinal configurations as shown in FIGS. 14 - 1 (A) and (B). Specifically, each separator has thinned leading and inner edge portions. Preferably, the leading edge of each separator is more sharpened than the inner edge.

By the arrangement and sectional configuration of each of the separators 38 and 38', the inwardly folded portions 35 of the tube 13' are gradually separated as will be seen in FIG. 14 - 2 to ensure that the separated outer edges of the tube 13' are gripped by the chuck

units 40 and 41. More specifically, since each of the separators 38 and 38' is arranged to have an angle of advancement α , as discussed above, the inwardly folded portions 35 are initially separated at the portion 5 adjacent the inner folded edge, as will be seen in FIG. 14 - 2 (F). The separation proceeds outwardly. For this reason, the tube 13' receives forces which tend to expand the tube in widthwise direction and thus advantageously avoid a disadvantageous possibility that longitudinal wrinkles are otherwise produced in the flat faces of the tube 13' in the course of the sealing operation by the sealing and cutting means 28. The inner edges of the separators 38 and 38' are spaced outwardly from the inner folded edges of the folded portions 35 of the tube 13' so as to avoid the production of wrinkles in the tube 13' although the inner edges of the separators 38 and 38', if extended into contact with the inner folded edges in the tube 13', might serve to laterally support the tube 13' against lateral oscillation. 10 15 20

With the apparatus of the present invention, the guide rollers 29 are provided with rings or flanges 72 which laterally support the tube 13' against such a lateral oscillation. 25 30 35 40 45 50

The sealing and cutting means 28 will be described with reference to FIGS. 15 to 18. Referring to FIG. 16, the sealing and cutting means 28 include a heater unit 80 disposed on one side of the tube 13' while a presser 81 is disposed on the opposite side of the tube 13' in laterally opposed relationship with the heater unit 80. A pair of members 82 and 82' for holding the tube 13' in a tensioned state during the severing operation are disposed under the heater unit 80 and the presser 81, respectively, in laterally opposite relationship to each other. The heater unit 80 is secured to the tube holding member 82 while the presser 81 is slidably mounted on the tube holding member 82'. Resilient elements 83, 84 and 84' are secured to the inner surfaces of the presser 81 and the tube holders 82 and 82', respectively, to act as cushioning members. The resilient element 83 is required to be heat resistant and thus is preferably made of silicone rubber. The presser 81 is backed up by a compression spring 85 which resiliently urges the presser 81 against the heating unit 80 during the sealing of the tube 13'. The other or rear end of the spring 85 abuts against a spacer element 87. A top plate 86 is mounted on the spacer element and the presser 81. A pin 88 fitted at the opposite ends to the tube holder 82' and the top plate 86 extends loosely through a slot 81' in the presser 81 to allow the same to have a limited sliding movement.

One of the tube holding members 82 is formed by a pair of plate-like elements between which is formed a cavity in which a cutter blade 89 is mounted on a cutter holder 107 in such a manner that the blade is moved out of the cavity by a link and lever mechanism to be described later through an opening 90 into cutting engagement with the tube 13'. The other tube holding member 82' is formed with a recess 90' in a position to accommodate the cutting edge of the cutter blade 89 when the same is moved out of the tube holder 82 to sever the tube 13'. The tube holding members 82 and 82' are fixedly mounted on sliding plates 91 and 91', respectively, which are slidably movable toward and away from each other on support plates 92 and 92' by means of pins 93 and 93' having one end secured to the sliding plates 91 and 91' and extending through slots in the support plates 92 and 92' and connected at the 55 60 65

other end to lever mechanisms 94 and 94' for actuating the major portions of the seal and cutting means 28.

A motor 96 is mounted on the support plate 92 adjacent one of the ends thereof, as best shown in FIG. 15. As shown in FIG. 17, the motor has its output shaft connected to a crank arm 97 which in turn is drivingly engaged with one of the arms of an L-shaped master lever 98 pivotally mounted on the support plate 92 so that the lever 98 is oscillated by the crank arm. The lever 98 has its other end pivotally connected to one end of a connecting rod 99 which is pivotally connected to one end of a pair of L-shaped levers 94 pivotally mounted at their intermediate portions to the support plate 92. The other end of the connecting rod 99 is connected to one end of a chain 100 extending around sprockets 102 and 102' rotatably mounted on the support plates 92 and 92', respectively. The other end of the chain 100 is connected to a spring 101 which in turn is connected to a connecting rod 99' to which are pivotally connected a pair of L-shaped levers 94' pivotally mounted on the support plate 92'. Thus, it will be appreciated that the oscillation of the master lever 98 is simultaneously transmitted by the connecting rods 99 and 99', the chain 100 and the spring 101 to the L-shaped levers 94 and 94' on the support plates 92 and 92'. The other ends of the levers 94 and 94' are connected to the pins 93 and 93', as best shown in FIG. 16, so that the oscillation of the master lever 98 moves the sliding plates 91 and 91' and all the elements of the sealing and cutting means on the sliding elements toward and away from each other with respect to the support plates 92 and 92'. A tension spring 103 is advantageously provided between the connecting rod 99' and the corresponding support plate 92' to bias the connecting rod in a direction to keep the chain in a tensioned state so that the connecting rod 99' is caused to positively act on the associated levers 94' as the connecting rod 99 acts on the levers 94 for the opening movement of the sliding plates 91 and 91'.

When the sealing and cutting means are closed to pinch the tube 13', the cutter blade 89 is actuated to move into severing engagement with the tube by a motor 104 mounted on a bracket 105 secured to the outer surface of the tube holding member 82. The output shaft is drivingly connected to the blade holder 107 through a crank arm, a link member 106 and a lever 95, which is pivotally mounted on the member 82, so that the cutter blade is moved not only in its widthwise direction but also in the longitudinal direction to saw the tube 13'. The sealing and cutting means 28 described above are reliably operable to seal and sever successively supplied lengths of tube of a thermoplastic material without producing any wrinkle in the tube for successively producing a large number of open-topped sacks which will be moved to the next station in the apparatus.

Referring to FIG. 18, the heater unit 80 of the sealing and cutting means 28 has a heater circuit which includes a heater 110 and a resistor 111 for restricting the electrical current therethrough. A relay 112 which is operable by a faint electrical current is series-connected to the resistor 111. Normally, electric current far less than the rated current for the heater 110 is supplied to this circuit. The relay will be inoperable if a breakage takes place in the heater 110. A switch 113 is connected to the circuit in parallel with the resistor 111 and the relay 112. When the sealing means are

closed, the switch 113 is operative in response to a sealing signal to supply to the heater 110 the rated electric current therefor. Since the relay 112 is inoperative at this time, it must be known if the heater is broken. For this purpose, there is provided another circuit which includes a switch 114, a switch 115 and a second relay 116 all connected in series. The switch 114 is operative in the opposite sense relative to the switch 113. When the switch 113 is closed, the switch 114 is opened and thus the relay 116 is made inoperative. On the other hand, when the switch 113 is opened, the switch 114 is closed. If there occurs a breakage in the heater 110, the relay 112 is switched off and the relay 116 becomes operative to emit a signal which represents the breakage in the heater. Reference numeral 117 in FIG. 18 represents electric contacts of the relay 116 while numeral 118 denotes a warning lamp which is energized by the relay 116.

It will be appreciated that the heating unit 80 of the sealing and cutting means 28 is provided with a heater breakage detecting means which is simple in circuit arrangement and which reliably operates to facilitate watching of the sealing means of the apparatus. Moreover, the heater breakage detecting means is efficiently applicable to a case in which the operation in each cycle requires a substantial amount of time for only a part of which current is supplied to the heater.

The sealing means (not shown) for closing the top of each sack may also be provided with similar electric circuits.

Referring to FIGS. 22 and 23, grippers 37 are mounted at a predetermined interval on each of the conveyor chains 37. Principally, each gripper 36 comprises a gripper body 120 secured to one of the chains 36 and a lever 121 pivotally mounted on the gripper body 120 by means of a pin 123. A projection 122 is provided on the inner surface of the forward or lower end portions of the lever 121. A spring 124 is mounted on the pin 123 in such a manner that the lower end portion is biased toward the gripper body 120 to urge the projection against the body 120 so that the tube 13' is positively pinched at a portion between the gripper body 120 and the projection 122. When the above-described chuck units 40 and 41 are moved upwardly with the leading edge portion of the tube 13' gripped thereby, the levers 121 of several grippers 37 are actuated by pressure plates 125 so that the lower end portions of the grippers 37 are moved apart from their gripper bodies 120 so as to be prepared for the receipt of the top end of the tube 13'. When the top end of the tube is inserted between the body 120 and the lower end portion of the lever 121 of each gripper 37, the corresponding pressure plate 125 is moved upwardly to release the upper end portion of the gripper lever 121 so that the latter is rotated about the pin 123 by the spring 124 into gripping engagement with the tube 13'.

The pressure plates 125 are provided on a frame member 128 which is slidably mounted on a pair of vertical bars 127 supported by bracket members 126 which in turn are secured to a base 129'. The frame member 128 is disposed above the sack producing section I of the apparatus in such a position that the pressure plates 125 extend over grippers 37 of a number required for transporting a sack. The frame member 128 is adapted to be downwardly actuated by a solenoid 129 mounted on the base 129' and connected to the frame member 128 by means of a pin 94 so that the

pressure plates are moved into pressure contact with the upper ends of the grippers 37 for opening the same as described.

In the illustrated embodiment of the invention, six grippers 37 are used to support a sack from the chains 36, four grippers being adapted to grip the top portions of the four outer corners or edges of a sack while the remaining two grippers are adapted to grip the top edges of the two flat major surfaces of the sack at intermediate portions.

As described, the gripping levers of the grippers 37 are actuated by a single solenoid 129 for the simultaneous opening of six grippers. In addition, the gripping levers 37 are spring-loaded for the closing of respective grippers. Thus, the grippers 37 are economically and reliably operable by a simple and inexpensive arrangement and construction.

Referring then to FIGS. 19 to 21, the conveyor chains 36 extend over the sack producing section I, the goods introducing section II and the sack top sealing section III. A sack 13 or 13a produced by sealing the tube 13' and severing the tube is gripped by grippers 37 on the chains 36 and conveyed from the sack producing section I to the goods introducing section II by means of the conveyor chains 36. In the goods introducing section II, the conveyor chains 36 are guided by guides 131 so as to be laterally separated so that the space between the chains 36 is widened, as best shown in FIG. 19, to cause the top of the sack to be opened wide for the preparation of receipt of goods introduced thereinto through the inlet opening 2 or 3.

As will be seen in FIG. 20, the bottom of the sack 13 is supported by a belt conveyor 132 disposed at the bottom portion of the goods introducing section II so that the weight of the goods in the sack is supported by a motor 133 having a sprocket 134 which is drivingly connected by an endless chain 135 to a second sprocket 136 to which one of the drums for the belt conveyor 132 is connected. The conveyor chains 36 are stopped for a while during the loading of the goods of a purchaser into the sack. When all of the goods are placed in the sack, the conveyor chains 36 are again moved to convey the loaded sack to the sack top sealing section III. The bottom conveyor 132 and another belt conveyor 137, which is disposed at the bottom of the section III, are also moved in synchronism with the upper conveyor chains 36. A second pair of sprockets 130a for the upper chains 36 are provided between the sections II and III so that the widened space between the upper conveyor chains 36 are narrowed to the initial dimension to close the open top of the loaded sack. The closed top of the sack will be automatically sealed by another sealing means 138 to form a top seam 139. The sealing means 138 may be substantially identical in construction to the afore-described sealing and cutting means 28 with the exception that the sealing means 138 does not require a cutting means. For this reason, further illustration and description on the sealing means 138 are omitted.

The bottom conveyor belt 137 is driven by a motor 140 having a sprocket 141 which is drivingly connected by an endless chain 142 to another sprocket 143 which in turn is connected to one of the drums for the belt 137 which extends around three drums. Another drum for the belt 137 is disposed adjacent one of the drums for the belt 132. The other drum 155 for the belt 137 is disposed at a level higher than the second drum for

the belt 137 while the first drum for the belt 137 is disposed substantially at the same level as the drum 155 so that the belt 137 is provided with an upwardly inclined transition portion 156 which merges at the point of the drum 155 into the upper horizontal run of the belt 137 which is disposed at a level elevated a distance s higher than the upper run of the belt 132. With this arrangement, the sack loaded in the section II is smoothly transferred from the upper run of the belt 132

10 to the elevated upper run of the belt 137 which serves to lift the loaded sack so as to advantageously prevent the grippers 37 from being caused to support the entire weight of the goods in the sack during the sealing of the loaded sack adjacent the top thereof by the sealing

15 means 138 with a result that the loaded sack is still gripped at the top edge thereof by the grippers to facilitate the top closing and sealing operation. The belt 137 will be stopped for a while during the top closing and sealing.

20 When the loaded sack is closed and sealed at the top thereof, the grippers 37 are actuated to release the sack by a second gripper actuating means (not shown) which is disposed above the sack top sealing section and which may be identical in construction to the gripper actuating means discussed in conjunction with FIGS. 22 and 23. Simultaneously, the belt 137 is again driven to convey the packed goods to the delivery section IV, shown in FIG. 3, in which a downwardly inclined platform 20 is provided to receive the packed

25 goods and cause the same slide slowly down to an end plate 18 having an inner or stop face 19 which is advantageously formed of a soft and resilient cushioning material such as foamed rubber so as to prevent the goods from being accidentally damaged.

30 As shown in FIGS. 19 and 20, the upper conveyor chains 36 are driven by a motor and reduction gear assembly 144 having an output shaft to which is fixed a bevel gear 145 in meshing engagement with a second bevel gear 146 on one end of a transmission shaft 147

35 having the other end secured to a small spur gear 148 which in turn is in meshing engagement with a large spur gear 150 which is meshed with a second large spur gear 149 of the same diameter as that of the gear 150. The gear 150 is coaxially fixed to a sprocket 142 for rotation therewith while the gear 149 is similarly fixed to a sprocket 151, the sprockets 151 and 152 forming one end of the paths of travel of the conveyor chains 36. Similar sprockets 153 and 154 are disposed at the other ends of the paths of travel of the chains 36 so that one of the chains runs around the sprockets 151 and 153 while the other chain extends around the sprockets 152 and 154.

40 Referring to FIGS. 24, 25A and 25B and 29, the apparatus of the invention is advantageously provided with a means 160 for inwardly folding the side faces of a loaded sack at the upper portions thereof to facilitate top closing and sealing of the sack by the sealing means 138. The folding means 160 is provided between the goods introducing section II and the sack top sealing

45 section III of the apparatus and includes an upstanding base 160' mounted on a stationary machine frame. A motor 167 is mounted on the side face of the base 160' remote from the path of travel of loaded sacks. The motor 167 has an output shaft rotatably extending through the base 160'. A hub 161' is fixedly mounted on the free end of the output shaft of the motor 167. A generally triangular arm 161 is connected at one of

the apexes to the hub 161'. On the outer side of the triangular arm 161 is preferably mounted a bar-like flexible and resilient member 162 by means of a bolt 16 and a retainer 164 in such a manner that the resilient member 162 has one end portion extending substantially circumferentially of the hub 161' beyond another apex of the arm 161 into the path of the travel of the upper portions of loaded sacks 13.

The hub 161' is formed thereon with a first cam 165 which, when the arm 161 is moved to an elevated position A shown in FIG. 25B, is brought into engagement with a contact 166 of a microswitch 168 for stopping the motor 167. The hub 161' is also formed thereon with a second cam 169 which, when the arm 161 is moved from a lowered position C shown in FIG. 25B to an intermediate position B shown in FIG. 25A, is designed to actuate a contact 170 of a microswitch 171 for stopping the motor 167. The microswitch 171 is designed so as not to be actuated when the cam 169 is moved from the positions A to C shown in FIG. 25B. The motor 167 is a reversible motor and controlled by a timer (not shown) and the microswitches 168 and 171 so as to be started and stopped for the operation of the arm 161. An upper stop or safety pin 172 is mounted on the base 160' adjacent the microswitch 168 to prevent an accidental counterclockwise overrun of the arm 161 due to an accidental failure of operation of the microswitch 168. A bolt or stud 173 is mounted on the base 160' to limit the clockwise movement of the arm 161 thus to stop the arm in the lowered position C.

The operation of the sack folding means 160 will be described with particular reference to FIGS. 25A and B. When the folding means is not in operation, the arm 161 is in the intermediate position B shown in FIG. 25A. When a sack 13 or 13a is filled with goods at the goods introducing section II and is moved by the chains 36 toward the top sealing position III, the timer (not shown) will energize the motor 167 so that the arm 161 is rotated from the rest position B in a counterclockwise direction, i.e., in the direction opposite to that in which the loaded sack is forwarded. When the arm reaches the elevated position A, the cam 165 will actuate the contact 166 of the microswitch 168 so that the motor 167 and the arm 161 are stopped. In the course of the counterclockwise rotation of the arm 161, the arm 161 and the flexible member 162 are caused to rearwardly push the upper part of the leading side face of the loaded sack 13 for inwardly folding the leading side face as at 35 shown in FIG. 25A.

When the loaded sack 13 has reached the next position, a signal is emitted to the folding means 160 with a result that the arm 161 is rotated in clockwise direction from the position A to the position C to inwardly fold the trailing side face of the sack 13 at the upper part thereof, as shown by broken lines in FIGS. 25B. Thereafter, the timer controls the folding means 160 so that the arm 161 is then rotated in the counterclockwise direction from the position C to the position B in which the cam 169 actuates the microswitch 171 so that the arm 161 is stopped in this position for the next folding operation.

The embodiment shown in FIGS. 24, 25A and 25B is preferably provided with the flexible and resilient bar-like member 162 which is designed to be brought into engagement with the upper parts of the leading and trailing side faces of loaded sacks. However, the folding

means 160 does not necessarily need such a flexible and resilient barlike member. A modified embodiment of the folding means 160 shown in FIG. 29 is designed to achieve a similar purpose by direct engagement by the arm 161 itself with the upper parts of the leading and trailing side face of loaded sacks.

As described above, the folding means 160 is operable to advantageously inwardly fold the upper parts of the two opposite side faces of a loaded sack, i.e., the leading and trailing side faces of the sack, to enable the top closing and sealing means 138 to produce a neat closed top on a sealed sack. In addition, a single folding means 160 is sufficient to fold the two parts of a loaded sack. This contributes to economical manufacture of the apparatus.

The operation of the entire apparatus will then be described with reference to FIG. 26. When all the goods purchased by a customer are introduced by a cashier into the apparatus and it is judged that the packing operation can be started, she will push the packing initiation button 5 so that the conveyor chains 36 are started on their movements. In the sack producing section I, grippers 37 are opened and the tube 13' is moved forwardly or lifted by chuck units 40 and 41 a distance substantially corresponding to the height of a desired sack so that the top edge portion of the tube is gripped by the grippers 37. The chuck units then are lowered to their initial level. Thereafter, the tube 13' is sealed and severed by the sealing and cutting means 28 to form a sack.

In the course of the travel of the loaded sack to the sealing section III, the top portion of the leading side face of the sack is inwardly folded. The top portion of the trailing side face of the sack is inwardly folded immediately after the sack reaches the section III. After a moment while substantial part of the air in the sack is discharged therefrom, the sack is sealed adjacent the top thereof. The grippers 37 are then opened to release the sealed sack or the packed goods so that they are transferred by the belt 137 to the delivery section IV.

During the operation of the apparatus, the cashier may receive money from the customer. It will therefore be appreciated that the packing of goods and receipt of money can be simultaneously effected to appreciably shorten the time required for the cashier to deal with each of the customers.

In addition, since the goods introducing and top sealing sections II and III are provided with separate bottom conveyor belts, goods may be introduced into the apparatus at the section II while a preceding loaded sack is sealed at the top and transferred to the delivery section IV for the economical and efficient operation of the machine.

Moreover, since the sacks for packing goods with the apparatus of the invention are made of a tube of a liquid impermeable thermoplastic material, the sacks can be easily and automatically sealed to form packages of goods. The liquid impermeable nature of sacks makes it unnecessary to preliminarily wrap wet goods. Thus the present invention advantageously simplifies packing of goods and reduces the consumption of wrapping and packing materials.

With the embodiment of the invention described and illustrated above, large and small types of sacks are produced in two processing lines so as to be selectively used in accordance with a particular requirement by the bulkiness of goods. It will be understood that sacks

of the same sizes can be used in the different processing lines. In addition, the two lines can be started by a single initiation signal. Of course, the apparatus can have a modified form in which only a single processing line is provided.

The tube lifting and sack producing mechanism described with reference to FIGS. 5 through 12 may be modified as shown in FIGS. 27 and 28. The modified form of the tube lifting and sack producing mechanism includes a pair of chuck units 200 normally positioned below sealing and cutting means 201 which may be identical in structure with the sealing and cutting means 28 described above. The chuck units 200 are threadably engaged with upstanding threaded shafts 202 and 203, respectively, which are fixed at their bottom ends to bevel gears 204 and 203' which in turn are in meshing engagement with bevel gears 205 and 205' fixedly mounted on a driving shaft 206. The latter is driven by a motor (not shown) so that the chuck units 200 are simultaneously lifted a distance l substantially corresponding to the height of a required sack. When the chuck units 200 are lifted, the tube 13' is also lifted through the sealing and cutting means 201 to a position in which the top edge of the tube is located at a level 205 so as to enable the tube to be gripped by grippers 37 on the conveyor chains 36. When the tube 13' is so gripped, the chuck units 200 release the tube. Then the driving shaft 206 is rotated in the reverse direction to lower the chuck units 200 to their initial level at which the chuck units again pinch the tube 13'. Then the sealing and cutting means 201 are actuated to perform the intended sealing and severing of the tube. After the operation, the sealing and cutting means 201 are kept waiting for a next instruction signal. The upward and downward movement of the chuck units 200 are controlled by means of limit switches 207 and 208 which are designed to detect the chuck units at the upper and lower limits of the range of the upward and downward movement of the chuck units.

The chuck units 200 are interconnected by a pair of laterally or horizontally spaced elongated connecting members or plates 209 and 210 between which are disposed two sets of tube pinching mechanisms each comprising a pair of pivotal levers 211 and 212 having projections 213 and 214 formed on the outer surfaces of the levers adjacent their one ends. The levers 211 and 212 are secured at the other ends to sectors 217 and 218, respectively, which in turn are pivotally mounted on pins 215 and 216, respectively. One of the sectors 217 is connected through a link member 211', a pin 220, a second link member 219 and a second pin 221 to a solenoid 222 so that, upon actuation of the solenoid 222, the levers 211 and 212 are rotated toward each other, i.e., away from the connecting members 209 and 210, respectively, against the force of a spring 223 which biases the levers 211 and 212 toward the connecting members 209 and 210 to pinch two outer edges of the folded portions 35 of the tube 13' between the projections 213 and 214 and the associated connecting members 209 and 210, respectively.

What is claimed is:

1. A packing apparatus comprising means for producing sacks from a liquid impermeable packing material such as plastic film, means for introducing goods into each of said sacks to load the sacks, means for sealing the loaded sacks adjacent the top thereof to pack the goods, means for delivering the packed goods, and

conveyor means supporting the sacks at a predetermined pitch and operative in response to a packing initiation signal to convey the sacks to processing positions, in which said sack producing means comprises

- 5 means for supplying lengths of a tubular film material, means for lifting the tubular film material to a predetermined level at which the film material is supported at the top portion thereof by said conveyor means, and means for sealing and severing the thus supported film material along predetermined lines transverse to an axis of the film material to form a sack, and wherein said film material is in the form of a tube having opposite sides folded inwardly with the outer edges of each of the folded sides being disposed in close contacting relationship with each other, and in which said lifting means includes a chuck mechanism equipped with means operative to pinch the tube at the outer edges of the inwardly folded sides thereof in such a manner that said outer edges are separated from each other.
- 10 2. A packing apparatus comprising means for producing sacks from a liquid impermeable packing material such as plastic film, means for introducing goods into each of said sacks to load the sacks, means for sealing the loaded sacks adjacent the top thereof to pack the goods, means for delivering the packed goods, and conveyor means supporting the sacks at a predetermined pitch and operative in response to a packing initiation signal to convey the sacks to processing positions, in which said sack producing means comprises
- 15 means for supplying lengths of a tubular film material, means for lifting the tubular film material to a predetermined level at which the film material is supported at the top portion thereof by said conveyor means, and means for sealing and severing the thus supported film material along predetermined lines transverse to an axis of the film material to form a sack, and wherein said film material is in the form of a tube having opposite sides folded inwardly with the outer edges of each of the folded sides being disposed in close contacting relationship with each other, and in which said lifting means includes a chuck mechanism equipped with means operative to pinch the tube at the outer edges of the inwardly folded sides thereof in such a manner that said outer edges are separated from each other.
- 20 3. A packing apparatus comprising means for producing sacks from a liquid impermeable packing material such as plastic film, means for introducing goods into each of said sacks to load the sacks, means for sealing the loaded sacks adjacent the top thereof to pack the goods, means for delivering the packed goods, and conveyor means supporting the sacks at a predetermined pitch and operative in response to a packing initiation signal to convey the sacks to processing positions, in which said sack producing means comprises
- 25 means for supplying lengths of a tubular film material, means for lifting the tubular film material to a predetermined level at which the film material is supported at the top portion thereof by said conveyor means, and means for sealing and severing the thus supported film material along predetermined lines transverse to an axis of the film material to form a sack, and wherein said film material is in the form of a tube having opposite sides folded inwardly with the outer edges of each of the folded sides being disposed in close contacting relationship with each other, and in which said lifting means includes a chuck mechanism operative to pinch the tube at the outer edges of the inwardly folded sides thereof in such a manner that said outer edges are separated from each other, said chuck mechanism comprising a lever mechanism and a solenoid for actuating said lever mechanism, said lever mechanism including a pair of lever members, said solenoid being operatively connected to said lever mechanism so that said lever members are moved into and out of pinching engagement with the outer edges of one of the inwardly folded sides of said tube.
- 30 4. A packing apparatus according to claim 2, in which said chuck mechanism includes flexible cushioning elements adapted to pinch each of the outer edges of one of the inwardly folded sides of said tube.
- 35 5. A packing apparatus according to claim 2, in which said lever members are always biased in such a direction as to cause one end thereof to be moved to pinch said tube, and a cam means is provided so as to be actuated by said solenoid to operate said lever members against said bias.
- 40 6. A packing apparatus according to claim 2, in which said lever members are always biased in such a direction as to cause one end thereof to be moved to pinch said tube, and a cam means is provided so as to be actuated by said solenoid to operate said lever members against said bias.
- 45 7. A packing apparatus comprising means for producing sacks from a liquid impermeable packing material such as plastic film, means for introducing goods into each of said sacks to load the sacks, means for sealing the loaded sacks adjacent the top thereof to pack the goods, means for delivering the packed goods, and
- 50 8. A packing apparatus comprising means for producing sacks from a liquid impermeable packing material such as plastic film, means for introducing goods into each of said sacks to load the sacks, means for sealing the loaded sacks adjacent the top thereof to pack the goods, means for delivering the packed goods, and
- 55 9. A packing apparatus comprising means for producing sacks from a liquid impermeable packing material such as plastic film, means for introducing goods into each of said sacks to load the sacks, means for sealing the loaded sacks adjacent the top thereof to pack the goods, means for delivering the packed goods, and
- 60 10. A packing apparatus comprising means for producing sacks from a liquid impermeable packing material such as plastic film, means for introducing goods into each of said sacks to load the sacks, means for sealing the loaded sacks adjacent the top thereof to pack the goods, means for delivering the packed goods, and
- 65 11. A packing apparatus comprising means for producing sacks from a liquid impermeable packing material such as plastic film, means for introducing goods into each of said sacks to load the sacks, means for sealing the loaded sacks adjacent the top thereof to pack the goods, means for delivering the packed goods, and

conveyor means supporting the sacks at a predetermined pitch and operative in response to a packing initiation signal to convey the sacks to processing positions, in which said sack producing means comprises means for supplying lengths of a tubular film material, means for lifting the tubular film material to a predetermined level at which the film material is supported at the top portion thereof by said conveyor means, and means for sealing and severing the thus supported film material along predetermined lines transverse to an axis of the film material to form a sack, and wherein said film material is in the form of a tube having opposite sides folded inwardly with the outer edges of each of the folded sides being disposed in close contacting relationship with each other, and in which said lifting means includes a chuck mechanism operative to pinch the tube at the outer edges of the inwardly folded sides thereof in such a manner that said outer edges are separated from each other, and further comprising a member disposed upstream of said chuck mechanism and extending into said tube between the opposite outer edges of each of the inwardly folded sides of said tube for separating said opposite edges, said separating member being so arranged that a part of said separating member adjacent the longitudinal axis of said tube is advanced further with respect to the movement of said tube than the remaining part of said separating member.

6. A packing apparatus comprising means for producing sacks from a liquid impermeable packing material such as plastic film, means for introducing goods into each of said sacks to load the sacks, means for sealing the loaded sacks adjacent the top thereof to pack the goods, means for delivering the packed goods, and conveyor means supporting the sacks at a predetermined pitch and operative in response to a packing initiation signal to convey the sacks to processing positions, in which said sack producing means comprises means for supplying lengths of a tubular film material, means for lifting the tubular film material to a predetermined level at which the film material is supported at the top portion thereof by said conveyor means, and means for sealing and severing the thus supported film material along predetermined lines transverse to an axis of the film material to form a sack, and wherein said film material is in the form of a tube having opposite sides folded inwardly with the outer edges of each of the folded sides being disposed in close contacting relationship with each other, and in which said lifting means includes a chuck mechanism operative to pinch the tube at the outer edges of the inwardly folded sides

thereof in such a manner that said outer edges are separated from each other, said chuck mechanism comprising a pair of chuck units interconnected by a bar member, one of said chuck units being guided by and movable along an upstanding guide post, the other chuck unit being associated with a roller which is guided by and movable along an upstanding channel member.

7. A packing apparatus according to claim 6, in which one of said chuck units is movable widthwise of said tube so as to stretch the same in the widthwise direction thereof.

8. A packing apparatus comprising means for producing sacks from a liquid impermeable packing material such as plastic film, means for introducing goods into each of said sacks to load the sacks, means for sealing the loaded sacks adjacent the top thereof to pack the goods, means for delivering the packed goods, and conveyor means supporting the sacks at a predetermined pitch and operative in response to a packing initiation signal to convey the sacks to processing positions, in which said sack producing means comprises means for supplying lengths of a tubular film material, means for lifting the tubular film material to a predetermined level at which the film material is supported at the top portion thereof by said conveyor means, and means for sealing and severing the thus supported film material along predetermined lines transverse to an axis of the film material to form a sack, and wherein said film material is in the form of a tube having opposite sides folded inwardly with the outer edges of each of the folded sides being disposed in close contacting relationship with each other, and in which said lifting means includes a chuck mechanism operative to pinch the tube at the outer edges of the inwardly folded sides thereof in such a manner that said outer edges are separated from each other, said chuck mechanism including a pair of chuck units rigidly connected to each other, said chuck units being threadably engaged with upstanding threaded shafts which are adapted to be driven to upwardly and downwardly move said chuck units.

9. A packing apparatus according to claim 8, in which said chuck mechanism includes a pair of spaced connecting members extending between and interconnecting said chuck units, each chuck unit including a pair of lever members extending between said connecting members, a pair of mutually engaging pivotable segments each connected to one of said lever members, and a solenoid operatively connected to one of said segments.
